CLAIM

The ornamental design for a pin extractor for lens fining
and polishing machines, as shown and described.

DESCRIPTION

FIG. 1 is a perspective view of my pin extractor for lens
fining and polishing machines showing my new design;
FIG. 2 is a left side elevational view thereof, the right
side being a mirror image;

FIG. 3 is a front elevational view thereof;

FIG. 4 is a rear elevational view thereof;

FIG. 5 is a top plan view thereof; and

FIG. 6 is a bottom plan view thereof.

Fig. 1.

Fig. 6.

Fig. 5.
